ATTORNEY.

UNITED STATES PATENT OFFICE.

VICTOR SAVIO, OF WASHINGTON, DISTRICT OF COLUMBIA.

FOUNTAIN PEN.

Application filed May 25, 1927. Serial No. 194,177.

This invention relates to an improvement in fountain pens, wherein provision is made for utilizing substantially the entire barrel of the pen as an ink reservoir; means being provided whereby the pen may be readily and conveniently filled with ink.

The primary object of the present invention is the provision of means, adapted to occupy but a very small proportion of the length of the pen barrel, and through which the ink may be drawn into the barrel by external suction; the filling means permitting the convenient withdrawal of air to cause the ink to enter the barrel and being automatically closed against the passage of ink as the level of the latter reaches the filling means.

The invention is illustrated in the accompanying drawings, in which the figure represents a section, partly in elevation, showing my improvement applied to a pen.

The improved pen comprises a barrel 1, of conventional form exteriorly and of any appropriate size commensurate with the type of pen contemplated. At what may be referred to as the upper end the barrel is provided with a means to permit a filling of the barrel with ink or other fluid. This so-called filling means comprises spaced abutments 2 and 3 secured within the barrel and formed with central aligned openings 4. A valve member 5 is arranged and operative between the proximate surfaces of the abutments 2 and 3, this valve having a stem 6 extending into the opening 4 of the lower abutment and a stem 7 passing through the opening 4 of the upper abutment. The valve proper 5 is of flexible material capable of serving as a seal, such for example as soft rubber, the diameter of the valve, of course, exceeding the diameter of the openings 4 in the abutments. The space in which the valve is permitted play, that is the space between the proximate surfaces of the abutments 2 and 3, is particularly important, as this space must be such as to permit only a slight play of the valve in the operation of filling the pen, as will later appear.

The upper end of the barrel is reduced at 8 and exteriorly threaded to receive a cap 9, having an exterior diameter corresponding with that of the barrel to avoid any obstruction at this point. The cap is adapted for a limited threaded movement, being held against complete displacement from the pen barrel in any appropriate or desired manner.

The pen barrel at the shoulder formed by the reduced portion is formed with an opening 10, normally sealed when the cap is in closed position and open when the cap has been given approximately a half turn. The extended stem 7 of the valve bears beneath the cap 9, the relation being such that when the cap is in closed position the valve will be held to close the opening 4 in the lower abutment 3, while when the cap is in open position, the valve is free to move in the space between the abutments.

When it is desired to fill the pen, the pen end thereof is inserted in a body of ink after the cap has been moved to inoperative or open position, the cap 9 given a partial rotation to open the vent 10 and relieve pressure on the valve 5. Suction is then applied to the upper end of the barrel, as for example by the mouth of the user, and ink is drawn into the barrel from the pen end. In this operation it has been found that the air may be sufficiently exhausted from the barrel to permit the atmospheric pressure on the surface of the ink in the container to force the ink up into the barrel. This air withdrawal is not sufficient in volume or pressure to lift the valve 5 to close the opening 4 in the upper abutment 2, hence the ink will continue to flow into the barrel until the upper level thereof reaches the valve and floats the same against the lower end of the opening 4 of the abutment 2, sealing the opening against the passage of ink and insuring that no ink can pass the valve and hence reach the mouth of the user. Notwithstanding repeated experiments, the valve has been found to function in every instance exactly as described, this operation depending upon the play permitted the valve between the abutments. If the space here is correct, air may be freely withdrawn from the barrel without permitting the ink to pass the valve.

After the barrel has been filled, the cap 100 is turned to closed position, sealing the vent 10 and at the same time forcing the valve to close the upper end of the opening 4 in the lower abutment 3 to prevent any ink from reaching above the abutment in the tilting of 105 the pen or the like.

The important feature of the pen described is the fact that without material change in the conventional size, substantially double the usual ink capacity is provided. Furthermore, the pen readily lends itself to a thorough cleansing, as water or other cleansing

fluid may be drawn into and ejected from the barrel by suction and pressure through the agency of the mouth and lungs, thoroughly cleansing all parts. The operation in filling and using the pen is of the utmost simplicity, there being no parts to get out of order, and beyond obvious manipulation of the cap 9, no particular attention is required to secure the desired results. The simplicity and few parts of the pen command it from a commercial aspect, particularly when such parts are inseparable from the pen and require no adjustment or manipulation on the part of the user to secure the desired results.

10 The ink will feed readily from the pen, it being understood that the opening 15 is of appropriate size to take care of the flow, though if desired, in the event of stoppage of the flow through a thickening of the fluid or an 15 extremely small quantity thereof in the barrel, the cap 9 may be turned to admit air through the vent 10 and immediately thereafter closed, permitting ink delivery by gravity restricted by the size of the opening leading to the pen point.

20 The material of the various parts other than that of the valve 5 may be the conventional material employed in constructing fountain pens, though obviously it may well be that the parts can, within the invention, be constructed of other material, for example the barrel and other parts may be constructed of transparent or semitransparent material to visibly indicate the quantity of ink in the 25 barrel, and additionally provide a more attractive implement. The material, so long as it permits the function desired, is of no particular importance so far as the invention is concerned and any and all kinds of appropriate material is contemplated for use.

30 It is of course to be understood that the

fountain pen contemplates the use of the usual pen point, but I consider it as within the spirit of the present invention as adapting the improved fountain pen for use with a pen point constructed of any desirable material other than that now employed; that is to say, the pen point may be constructed of the present material or any other material now known or hereafter known and serviceable for use as a pen point.

35 The arrangement of pen described lends itself admirably to the application thereto of a fixed pen clip 24, such being secured, as illustrated in the drawing, in the barrel. In this position, the pen clip is on the upper side of the barrel when using the pen, entirely out of the way of the fingers, and forms no obstruction, being thus ready to serve as a clip when desired and remaining a permanent part of the construction.

40 What I claim to be new is:

In a fountain pen, a barrel adapted to serve as a reservoir for ink, screw threads formed on the upper part of the barrel, the section 45 having the threads having a vent therein, a cap adapted to be threaded on the barrel and seating on a shoulder formed thereon, the said cap closing the vent opening, parallel abutments formed in the barrel adjacent the top, the said abutments being only slightly spaced from each other, and having a central opening through both of said abutments, a disk valve operating between the 50 said abutments and adapted to be seated on either of them, a valve stem passing through the said disk valve and extending through both openings, the upper end of the valve stem being engaged by the cap when in turned down position.

45 55 60 65 70 75 80 85

In testimony whereof I affix my signature.

VICTOR SAVIO.
